UNITED STATES PATENT OFFICE.

GEORGE J. RYMAL, OF DENVER, COLORADO.

STOVE.

1,125,183.

Specification of Letters Patent.

Patented Jan. 19, 1915.

Application filed May 23, 1914. Serial No. 840,392.

To all whom it may concern:

Be it known that I, George J. RYMAL, a citizen of the United States, residing at Denver, in the county of Denver and State of Colorado, have invented certain new and useful Improvements in Stoves, of which the following is a specification, reference being had to the accompanying drawings.

This invention relates to certain improvements in stoves and has relation more particularly to a combined hot water heater range, and the object of the invention is to provide a device of this general character having novel and improved means whereby 15 the waste heat from the hot water heater or boiler is utilized to heat the range element or member of the structure and an oven interposed in the smoke flue.

The invention consists in the details of 20 construction and in the combination and arrangement of the several parts of my improved stove whereby certain important advantages are attained and the device is rendered simpler, less expensive and otherwise 25 more convenient and advantageous for use, all as will be hereinafter more fully set forth.

The novel features of the invention will be carefully defined in the appended claim.

30 In order that my invention may be the better understood, I will now proceed to describe the same with reference to the accompanying drawings, wherein—

Figure 1 is a somewhat diagrammatic 35 view, partly in elevation and partly in section, of a combined water heater and range constructed in accordance with an embodiment of my invention, the incidental heating system being disclosed in connection 40 therewith; Fig. 2 is a view, partly in front elevation and partly in section, of the device as disclosed in Fig. 1; Fig. 3 is a fragmentary view in top plan of certain of the heating sections herein embodied, with the 45 pipe connection shown in fragment; and Fig. 4 is a view, detached, in top plan of the grate member herein embodied.

As disclosed in the accompanying drawings, 1 denotes the range element or member 50 of any desired configuration and being provided in its front face with a feed door 2 in communication with the fire box, a door 3 in communication with the ash pit, and a sliding draft door 4 positioned adjacent the 55 top thereof. As herein disclosed, the fire box and ash pit are separated by the grate

member 5, herein disclosed as segmental in cross section and in excess of a semi-circle and mounted for rocking movement and being provided with the extension 6 projecting exteriorly of the range element adapted to be engaged by a suitable implement whereby the requisite rocking movement may be imparted to the grate, as is believed to be self-evident.

65 Mounted within the fire box and directly above the grate 5 therein are the tubular water heating sections 7, each being substantially in the form of an inverted U, and having their lower free extremities suitably connected one with the other, as indicated at 8, while the upper portions are also connected one with the other, as indicated at 9. It is also to be observed that each of the heating sections is provided with the intersecting substantially horizontal member 10 and the vertical member 11 interposed between the top of the heating section and the transversely disposed member 10 whereby it will be readily perceived that an increased heating surface is presented which facilitates the requisite action on the water within the sections. An end section 7, preferably the rear section, has suitably connected with the top thereof, the hot 70 water pipe 12 which leads to a hot water radiator 14. While I have shown in the accompanying drawings but a single radiator 14 it is to be understood that the pipe 12 will be readily perceived that an increased heating surface is presented which facilitates the requisite action on the water within the sections. An end section 7, preferably the rear section, has suitably connected with the top thereof, the hot 75 water pipe 12 which leads to a hot water radiator 14. While I have shown in the accompanying drawings but a single radiator 14 it is to be understood that the pipe 12 may be connected with any desired number 80 of radiators. In communication with the free extremities of the inner section 7 are the branches 15 of the return pipe 16 from the radiator, whereby it will be readily perceived that a circulation of the water 85 for the purposes of heating is created in an effective and convenient manner.

In order that the top 17 of the range element may be used for conventional purposes, I position within the fire box and 90 above the sections 7 the partition 18, herein disclosed as terminating a predetermined distance inwardly of the forward face of the range element so that the heat together with the products of combustion from within 95 in the fire box will be caused to travel under the entire top so that the requisite heating influence will be had thereon. In communication with the fire box through the top 17 of the stove are the vertically disposed 100 smoke flues 19 in communication with the drum 20 from which the single smoke flue

21 is directed and positioned within the drum 20 is the oven 22, said oven being of such a size that the products of combustion delivered within the drum through the flues 19 may pass entirely therearound in order to properly heat said oven. In order that proper ingress may be had to the oven, the forward face of the drum 20 is provided with a conventional door 23. It is also to be observed that the flow of the products of combustion through the first flues 19 are under control of the dampers 24 which may be of any ordinary or preferred construction.

In order that heated water may be obtained for household purposes, I position within the upper portion of the fire box the coil 25, the upper extremity of which leads from a hot water pipe 26 in communication, as at 27, with a boiler 28 while the opposite extremity of the coil 25 is in communication with the base of the boiler 28 through the medium of the pipe 29.

30 indicates a surface pipe, as is generally employed.

It is to be observed that by having the grate member 5 segmental and disposed upwardly, the heated coals of the fire bed are caused to lie against the stems or legs of the sections 7, and this positioning of the heated coals is further assured by imparting to the grate member 5 transverse rocking action as has hereinbefore been referred to. It is also to be observed that the free extremities of the legs or stems of the sections 7 are curved

inwardly so that the same will be partly 3 embedded in the fire bed.

From the foregoing description, it is thought to be obvious that a stove constructed in accordance with an embodiment of my invention is of an extremely 40 simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

In combination, a fire box provided with an upwardly disposed grate member 55 segmental in cross section and in excess of a semi-circle, and a heating member disposed within the fire box above the grate member, said member being substantially U-shape in form, with its free extremities straddling 60 the grate member and terminating immediately adjacent thereto.

In testimony whereof I hereunto affix my signature in the presence of two witnesses.

GEORGE J. RYMAL.

Witnesses:

EDWARD WHITLEY,
MARION E. CARPENTER.
